Application March 26, 1934, Serial No. 717,530
In Sweden March 29, 1933

7 Claims. (Cl. 170—159)

The invention relates to propellers and more particularly to the shaping and disposition of the blades thereof.

The primary object of the invention is the provision of a propeller of this character wherein a higher degree of efficiency is attained and a more effective equalization of the rearward thrust and concentration of the force of the propeller.

Further objects and advantages to be attained will more fully appear in the following description:

The invention is equally applicable to propellers of both the marine and aircraft types and it consists essentially in the peculiar characteristics of a propeller having its blades inclined forwardly and uniformly curved in the direction of rotation and said blades having curvilinear cutting and trailing edges, with the working faces of the blades uniformly curved in a forward direction or in the direction of rotation as hereinafter described and pointed out with particularity in the appended claims.

In the accompanying drawing forming part of this application and illustrating practical adaptations of the invention

Figure 1 is a fragmentary elevation of a propeller blade of the marine type looking toward the working face thereof.

Figure 2 is a fragmentary vertical sectional view.

Figure 3 is an end view looking toward the tip of the blade.

Referring to the drawing in detail, particularly Figures 1 to 3 inclusive, 10 designates the blade of the propeller and 11 the hub, this carrying the hole for the mounting of the hub in the use of the propeller. The working face of the blade 10 is comparatively straight along the axial or radial lines a, b and c, respectively, and on a longitudinal line it is uniformly curved forwardly in the direction of rotation on a radius substantially equal to the length of the radius from the axis of the propeller to the peripheral end of the blade. d indicates the center from which the circular contour 12 of the tip of the blade is taken, while e is the point from which the cutting edge 13 of the blade starts at the hub 11 and through the radial line b and from which line f extends, while g identifies the angle between the radial line b and the line f, which is approximately thirty degrees.

The extreme forward point of the blade in the direction of rotation of the propeller is indicated at 14 this being on the cutting edge and the trailing edge of the said blade at 15 which point k at said trailing edge is approximately one-half the length of the radius of the propeller from the

center of the hub. h indicates the median between the point e and the point i and through which line j passes to the point k at the trailing edge 15, while the line l extends from the point h to the tip of circular formation 12, the angle between the points scribed by the arrows m being approximately forty-five degrees, which indicates the forward set of the blade in the direction of rotation, while from the points scribed by the arrows n is identified the trailing edge angularity which is approximately forty-five degrees. Any point of the arc of the curve of the trailing edge 15 intersects any of the axial radii, while the point i of the arc is fixed within the area of the periphery of the hub. The center of the hub 11 is indicated at the point o, while the line p from this center to the forward edge 14 of the said blade is a distance that this edge is forward of the direction of rotation of the propeller, while the lines q and r indicate the radius from which the cutting and trailing edges are drawn, respectively, the center for the radii r being indicated at s in Figure 2 of the drawing.

The lines t, u, v and w, as indicated in Figure 3 of the drawing, are the zones of the slight curvatures transversely of the blade, the curvatures being identified at x, y and z in Figure 1 of the drawing. Thus it will be apparent that the blade 10 has a concaved working face and is of screw form, inclined forwardly and uniformly curved in the direction of rotation of the propeller.

The cutting edges 13 and the trailing edges 15 of said blades are curvilinear and preferably truly arcuate, as will be presently described, and said blades are leaned forwardly in the direction of rotation, or, in other words, the outer or peripheral end portions are somewhat in advance of the inner or central end portions of the blade and the curved cutting and trailing edges, respectively, are circular.

The trailing edge 15 of the blade is curved on a radius substantially the same as the radius from the axis of the propeller to the end portion 12 of the blade, the center from which the curve is struck being located so that the line of said edge 15 beginning at a point substantially tangential to the hub crosses or intersects an imaginary radial line at a point approximately one-half the length of the latter. This determines the forwardly inclined set of the blade with respect to the direction of rotation thereof. The cutting edge 14 of the blade is also formed on the same radius as the trailing edge 15 but from a different center which is determined by the

relative widths of the blade at the inner and outer portions thereof.

In the operation of the propeller constructed and arranged according to the present invention, the forwardly inclined end portion of the blade is the first to attack the fluid in which the propeller is rotated and as its cuts through said fluid forces it inwardly along the transversely angular and longitudinal curved rearward face 5 of the blade and rearwardly from the blade, thereby concentrating the effective force of the propeller closely about the axis thereof. In other words, the displaced fluid is directed toward the center of the propeller so as to confine the propulsive effort of the propeller to a minimum area, the fluid being directed into a column revolving about the axis of the propeller and extending longitudinally in the surrounding fluid. The result of this action is the projection of a 10 restricted column of fluid which tends to contract and taper rather than disseminate or diverge as usually occurs as a result of the operation of the ordinary screw or radial blade propeller.

25 By the construction and arrangement of the propeller according to the present invention, the longitudinal thrust is equalized over the entire working surface of the propeller and by the resultant concentration of the displaced fluid into 30 a column immediately in rear of the propeller and in axial alignment therewith, the full reaction is available for propelling the ship whether it be of the marine or aircraft type.

35 While the structures illustrated in the drawing and described in the foregoing specification disclose practical and preferred adaptations of the invention, it is to be understood that the same admit of considerable modification and alteration within the spirit and scope of the invention as defined by the appended claims.

40 What is claimed is:

1. A propeller of the character described, comprising a hub portion and blades extending from said hub portion and each having changed pitch 45 on every transverse line of section throughout the length of the blade, the working face of the blade being uniformly curved forwardly in the direction of rotation, the forward outer end portions of said blades being in advance of the forward hub portions thereof, said blades having their cutting and trailing edges respectively curved on a radius equaling the radius from the axis of the propeller to the peripheral end of the blade, said cutting and trailing edges beginning tangentially to the hub portion on opposite ends thereof and merging roundly at the peripheral end of the blade.

55 2. In a propeller, a blade having a trailing edge which is curved on a radius substantially equal to the length of the radius from the axis of the propeller to the peripheral end of the blade, the working face of the blade being uniformly curved forwardly in the direction of rotation, one point of the arc of the said curve 60 being at the point of intersection of any of the axial radii, and the other point of the arc being fixed substantially in the area of the periphery of the usual hub of a propeller.

65 3. In a propeller, a blade having a trailing edge which is curved on a radius substantially equal to the length of the radius from the axis of the propeller to the peripheral end of the blade, the working face of the blade being uniformly curved forwardly in the direction of ro-

5 tation, one point of the arc of the said curve being at the point of intersection of any of the axial radii, and the other point of the arc being fixed substantially in the area of the periphery of the usual hub of a propeller, said curve beginning at a point substantially in the area of the periphery of the usual hub of a propeller, so as to intersect the said axial radius to extend to the peripheral end of the blade.

10 4. In a propeller, a blade having a trailing edge which is curved on a radius substantially equal to the length of the radius from the axis of the propeller to the peripheral end of the blade, the working face of the blade being uniformly curved forwardly in the direction of rotation, one point of the arc of the said curve being at the point of intersection of any of the axial radii, and the other point of the arc being fixed substantially in the area of the periphery of the usual hub of a propeller, said blade having 15 its outer end portion so constructed and arranged as to lead its inner end portion in the direction of rotation.

20 5. In a propeller, a blade having a trailing edge which is curved on a radius substantially equal to the length of the radius from the axis of the propeller to the peripheral end of the blade, the working face of the blade being uniformly curved forwardly in the direction of rotation, one point of the arc of the said curve 25 being at the point of intersection of any of the axial radii, and the other point of the arc being fixed substantially in the area of the periphery of the usual hub of a propeller, said blade having also a cutting edge formed on the same radius as the trailing edge, one point of the arc of the said cutting edge being substantially in the area of the said periphery, but being on the opposite end of the axis to the other point in the area of the said periphery, the other point of the arc of the cutting edge being struck from a different center to that of the trailing edge, depending upon the desired width of the blade.

30 6. A propeller having a blade with a trailing edge which is curved on a radius substantially equal to the length of the radius from the axis of the propeller to the peripheral end of the blade, the working face of the blade being uniformly curved forwardly in the direction of rotation, one point of the arc of said curve being at the point of intersection of any of the axial radii, and the other point of the arc being fixed substantially in the area of the outer periphery of the usual hub of a propeller, said blade being 35 set at a predetermined angle longitudinally of the hub throughout the length of the blade from the hub end portion to the peripheral end portion of the blade.

40 7. A propeller of the character described, comprising a hub portion and blades extending from said hub portion at varying angularity on every transverse line of section throughout the length of the blade, the forward outer end portions of said blades being in advance of the forward hub portions thereof, said blades having their cutting and trailing edges respectively curved on a radius equaling the radius from the axis of the propeller to the peripheral end of the blade, said cutting and trailing edges beginning tangentially to the hub portion on opposite ends thereof and merging roundly at the peripheral end of the blade.
